CHARGE FORMING DEVICE

Application filed July 17, 1928. Serial No. 293,424.

This invention relates to charge forming devices for internal combustion engines, and more particularly to that type of charge forming device which comprises a plurality 5 of primary carburetors for supplying a primary mixture of fuel and air to a plurality of secondary carburetors located adjacent the engine intake ports, and to which additional air may be supplied under certain operating conditions through a secondary air passage, for admixture with the primary mixture.

Examples of charge forming devices of this type are disclosed in the copending applications of Wilford H. Teeter, Serial No. 221,372, filed September 22, 1927, and Fred E. Aseltine, et al., Serial No. 288,683, filed June 10, 1928.

It is the general object of the present invention to provide improved means for controlling the proportions of fuel and air in the mixture, and more particularly, to provide improved means for enriching the mixture during the acceleration period, to provide a mixture rich enough in fuel content to give the necessary power for smooth and rapid acceleration.

More specifically, it is an object of the invention to provide means for temporarily restricting the admission of secondary air following any opening movement of the throttle, so that the enriched primary mixture is delivered to the intake ports without delay and without dilution by an excess of secondary air.

Further objects and advantages of the present invention will be apparent from the following description, reference being had to the accompanying drawings, wherein a preferred form of embodiment of the present invention is clearly shown.

In the drawings:

Fig. 1 is a plan view of the present invention attached to the engine cylinder head, a part of which is shown in section.

Fig. 2 is a side elevation looking toward the engine block.

Fig. 3 is a section on line 3—3 of Fig. 1. 50 Fig. 4 is a section on line 4—4 of Fig. 1.

Fig. 5 is a fragmentary detail section on the line 5—5 of Fig. 3.

Fig. 6 is a detail view of the primary throttle valve.

Fig. 7 is a side elevation of the main carburetor unit looking from the right in Fig. 2. 55

Fig. 8 is a side elevation of the main carburetor unit looking from the left in Fig. 2.

Fig. 9 is a detail sectional view, partly diagrammatic, showing the means for retarding the opening of the secondary air valve. 60

Fig. 10 is a section through the secondary mixing chamber on line 10—10 of Fig. 2.

Figs. 11 and 12 are detail sections at right angles to each other of the float valve mechanism and fuel inlet passage controlled thereby. 65

Fig. 13 is a detail section on the line 13—13 of Fig. 3.

It will be observed that the main air passage which admits air to the secondary mixing chambers has in some instances in this specification been termed a "secondary" air passage, while the air flowing through such 75 passage has been termed "secondary" air. These terms have been used to distinguish from the "primary" air passage and "primary" air which goes to the primary mixing chambers. 80

The device disclosed herein comprises a main air manifold indicated in its entirety by the reference character 10, and having three outlet branches 11, 12 and 13 each of which is adapted to communicate with one 85 of the ports 14 of a multicylinder engine. Each port serves two adjacent cylinders through valve ports 14a and 14b, as clearly indicated in Fig. 1. The cylinder head is shown in three separate fragments 15, but it will be understood that it may be an integral structure. The branches 11, 12 and 13 are each provided with an attaching flange 16, for attaching the manifold to the engine block in the conventional manner. Adjacent 90 the inlet of the manifold is provided a flange 17 to which may be secured the main carburetor unit as shown in Fig. 3.

The main carburetor unit comprises a main housing in the form of a single casting 18, 100

attached by screws 19 to the flange 17. An air inlet horn 20, the flow of air through which is regulated in a manner later described, is secured in position over an opening in the upper wall of said housing by screws 22 which pass through flanges 23 and 24 on the horn and housing respectively. A casting 25 having certain dashpot chambers and fuel passages, described in detail hereinafter, formed therein is secured by screws 26 to the lower wall of the main housing 18, a gasket being provided between the castings to make a tight joint, and a sheet metal fuel bowl 27 is held tight against a shoulder 28 on said main housing 18 by means of a screw 29 which is screwed into a post 30 depending from and integral with the casting 25.

A fuel line leading to a main source of fuel supply (not shown) is connected to a nipple 31, screwed into the main housing 18 as shown in Fig. 1. This nipple may have a screen secured therein in a manner well known so that incoming fuel must pass through the screen and said nipple communicates with a bore 32 formed in the wall of housing 18, the bore 32 connecting with bore 33 also in the wall of said housing as shown in Fig. 12. At its inner end the bore 33 connects with a vertical bore 34, which in turn communicates with a bore 35 in casting 25. A plug 36 is screwed into the lower end of bore 35 and is provided with lateral fuel outlets 37 through which the fuel flows into the float chamber. Cooperating with valve seat 38 is a valve 39 controlled by a float 40 pivoted at 41. The valve operates in the usual manner to maintain a constant fuel level in the said float chamber.

40 Fuel is conducted from the fuel bowl to a plurality of primary fuel nozzles 42 located in the primary mixing chambers 43 formed in the central part of the main housing which may be termed the distributor block. The 45 construction of the distributor block and co-operating elements comprising the primary carburetors will be more fully described hereinafter. To permit the fuel to flow from the fuel bowl to the primary nozzles 42 the casting 25 is provided with a vertical fuel channel 44 which communicates at its upper end with a horizontal fuel canal 45 which connects with each of the nozzles 42 through holes 46. Fuel is admitted from the fuel 50 bowl to the channel 44 at low speed through a metering orifice 47. All of the fuel flowing to the fuel nozzles 42 up to a certain predetermined engine speed, for example that corresponding to a vehicular speed of 20 miles per hour passes through the metering orifice 47. For higher speeds than said predetermined speed fuel is also admitted to the fuel channel 44 through an orifice 48 controlled 55 by a fuel valve 49, operated in a manner fully described hereinafter, and thence through a

horizontal channel 50, connecting with the lower end of channel 44.

Fuel is lifted from the fuel bowl through the nozzles 42 to the primary mixing chambers by the suction therein. When the throttle is moved toward closed position to reduce the engine speed there is a sudden reduction in suction on the vertical column of fuel between the fuel bowl and the nozzle which might permit this column of fuel to drop sufficiently to cause a temporary fuel starving of the engine unless means were provided to prevent the dropping of such column of fuel. To prevent this action a check valve 51 is received in an enlarged chamber 52 at the junction of channels 44 and 45 and on reduction of suction in the primary mixing chambers seats on the bottom of such chamber, preventing downward flow through the channel 44.

The metering orifice 47 is drilled in the casting 25 and the drill hole on the opposite side of the channel 44 is plugged by a screw 53.

Each primary fuel nozzle is shown herein as provided with a main fuel outlet in the top of the nozzle and a secondary fuel outlet comprising two holes 54 and 55 formed in the vertical wall of the nozzle and diametrically opposite each other as shown in Fig. 3. At higher speeds there is sufficient suction in the primary mixing chambers to cause fuel to flow from the main fuel outlet in the top of each primary nozzle, as well as from the holes 54 and 55. At idle or very low speed, however, there is insufficient suction to cause such a flow of fuel, the fuel at such time standing in the nozzle at a point between the top of the nozzle and the orifices 54 and 55, flowing from such orifices by action of gravity. Each fuel nozzle is provided with a restricted fuel metering orifice 56.

In the carburetor disclosed herein the central portion of the main casting constitutes the distributor block and is indicated at 60 in Fig. 3. The distributor block has three primary mixture passages 61, 62 and 63 formed therein, such passages being parallel to each other and close together as indicated in Fig. 5. These passages extend straight through the block, and passages 61 and 63 connect with L-shaped passages formed in the manifold, the outlet ends of such passages terminating in the side walls of the central branch of the manifold where they are connected with primary mixture pipes hereinabove described. The inlet ends of the primary mixture passages where the nozzles project into such passages are of larger diameter than the outlet ends thereof and between the inlet and outlet end of each passage its cross-sectional area is constricted as indicated at 64, such construction reducing the velocity of the air current passing the nozzle for a purpose hereinafter set forth.

The flow of primary mixture through the passages 61, 62 and 63 is controlled by a single throttle valve 65 which extends across all of the primary mixture passages, and has 5 grooves 66 therein which register with the said passages 61, 62 and 63. This throttle valve 65 is journaled in the housing 18 and has spindles 67 projecting from each end outside the housing 18 and on which certain 10 valve operating devices, hereinafter described, are secured. A groove 68 is provided in the throttle which cooperates with the inner end of a screw 69, adjustable in the casting, to prevent longitudinal movement of the said 15 throttle. The primary mixture passage 62 is in alignment with a tube 70 which is received in a boss in the branch 12, while the passages 61 and 63 communicate with pipes 71 and 72, respectively. These pipes are connected at one end to the outlets of passages 61 and 63 while the other ends of such pipes connect with elbows 74 detachably secured to the manifold branches 11 and 13, the outlet ends of such elbows being in alignment 20 with tubes 75 and 76 which are secured in manifold branches 11 and 13 respectively in any suitable manner. Primary mixture is drawn by engine suction from the primary mixing chambers through the pipe connections 25 above described, and tubes 70 and 75 and 76 to the secondary mixing chambers in which such tubes terminate. The primary mixture may be mixed with additional air in the secondary mixing chambers in a manner 30 more fully described later.

Substantially all the air entering the carburetor flows through the air horn 20, the flow therethrough being controlled by a main air valve 77, normally held against a seat 78 by a spring 79. Air flows past the valve 77 to a main air chamber 80 formed in the housing 18. An air conduit 81 controlled by a valve mechanism hereinafter described connects the air chamber with the main air manifold 45 while an orifice 82 in the floor of the air chamber permits a flow of air from the chamber 80 to the primary carburetors.

When the carburetor is choked to start the engine the air valve 77 is held against its seat by means presently described to completely close the main air inlet. To provide sufficient air to carry the starting fuel from the primary nozzles to the engine when the carburetor is choked as described an air inlet 55 83 is provided. This inlet is an elongated slot formed in a plate 84 secured to the housing 18 as shown in Fig. 3.

The main air valve 77 is adjustably secured on a stem 86 slidably mounted in a guide sleeve 87 fixed in the main housing 18. Surrounding the guide sleeve 87 is a slidble sleeve 88, the lower end of which has a projecting disc 89 secured thereto, the disc providing a seat for the air valve spring 79. 65 Means are provided for raising this sleeve

to a position where the upper end thereof will engage the air valve to hold it against its seat to choke the carburetor. This means comprises an arm 90 secured to a rock shaft 91 rotatably mounted in the wall of the main housing 18. The arm at its inner end has two pins 92 and 93 secured therein between which the disc 89 is received. The shaft 91 projects through the wall of the casing and at its outer end is bent to form an arm 200 70 having a hole 201 therein in which some form of operating connection, extending from a point convenient to the operator may be attached. An adjustable stop screw 202 is received in a lug detachably secured to the air horn as indicated in Fig. 2. By adjustment of the stop screw the normal position of the sleeve 88 may be determined to regulate the tension of spring 79. Ordinarily the stop screw is so adjusted that the main air valve will open slightly during idling. 75

During operation at all engine speeds below that corresponding to a vehicular speed of substantially 20-25 miles per hour on a level road the mixture formed in the primary carburetors is of properly combustible proportions and such mixture is conveyed to the engine without dilution by admixture with additional air in the secondary mixing chambers. At higher engine speeds, unless 80 means are provided to prevent such action, the velocity of the air current passing the nozzles becomes so great that a velocity head is built up at the nozzles and increases to such a degree that fuel is caused to flow from the nozzles rapidly enough to form a primary mixture which is super-rich in fuel content. To prevent this increase in fuel flow the air passage 81 leading from chamber 80 to the main air manifold is opened in a manner 85 hereinafter described, to permit a flow of air through the secondary air passage. This admission of air through the secondary air passage not only dilutes the mixture but also prevents as great an increase in air velocity 90 at the nozzles as would otherwise occur.

Flow of air from the chamber 80 to the secondary carburetors is controlled by two valves, a manually operated butterfly throttle 94 and a suction operated valve 95. The valve 94 is fixed on a shaft 96 which is journaled for rotation in the walls of the housing 18, and is operated simultaneously with throttle 65 through connections hereinafter described. The valve 95 is fixed to a shaft 97 which is positioned off center with respect to the valve, a greater portion of the valve being below the shaft than above. The shaft 97 is supported for rotation in the walls of the housing 18 and is operated primarily by 105 the engine suction, its operation being controlled by devices described later.

The operating connections for the throttle valves will now be described. Fixed on the end of one of the throttle spindles 67 outside 110

the housing 18 is an operating arm 98 having a hole in its free end to be connected to some suitable form of operating connection extending to a point convenient to the operator of the vehicle. This operating arm 98 is connected through a lost motion connection to an arm 99 secured by a split clamp to the end of shaft 96 outside the casing. An operating link 100 is pivotally connected to the arm 98, 5 and a pin 101 projecting from the free end of arm 99 projects through a slot 102 in the link 100. A regulating screw 103 is threaded in lugs 104 projecting from the operating link and may be adjusted to regulate the 10 length of the slot 102, the upper end of the said screw constituting the lower end of said slot. A tension spring 105 is connected at one end to the upper end of the link 100 and at its other end to the pin 101. The spring 15 tends to hold the pin 101 against the upper end of slot 102. With both throttles closed the parts are in the position shown in Fig. 9, with the pin 101 in engagement with screw 103. As the operating arm 98 is rotated in a 20 clockwise direction to open the primary throttle valve 65 the link 100 moves downwardly to a position where the upper end of slot 102 strikes pin 101 before the operating arm 99 of the air throttle 94 is moved so that 25 the primary throttle is partly opened before the air throttle begins to open. The screw 103 serves as a stop to limit the closing movement of the primary throttle and adjustment of said screw regulates the throttle opening 30 at idling.

On opening movement of either throttle valve the suction below the air valve 77 is increased and the air valve is opened against the tension of its spring permitting an 35 rush of air to the secondary mixing chambers which will be sufficient to lean the mixture unless means are provided to retard the opening movement of said valve. By retarding the opening of the valve the leaning of 40 the mixture as well as fluttering of the air valve may be prevented. It will be understood, of course, that opening of the air valve 45 may be sufficiently retarded on opening of the throttle to enrich the mixture for acceleration, but in this particular embodiment of 50 the invention opening of the air valve is not retarded to that extent.

To retard the opening movement of the air valve the lower end of the valve stem 86 has 55 secured thereto a piston 106 which slides in a cylinder 107 formed in the casting 25. The piston is secured to the stem 86 by means disclosed in the copending case above referred to, a nut 109 holding the piston in place. 60 The lower end of the cylinder is closed by a closure member 110, having a valve controlled inlet (not shown) therein, and permitting free upward movement of said piston, but retarding the downward movement thereof and 65 opening movement of the valve.

The dashpot cylinder 107 may be provided with a by-pass in its wall which allows liquid to pass around the piston when the piston passes below the upper end of said by-pass, thus relieving the dashpot. As this by-pass 70 forms no part of the present invention and its construction and function is fully described in the above mentioned application it is not shown herein.

When the main throttle valve 94 is opened 75 the suction in the chamber 80 below the air valve 77 is so greatly increased that although the suction at the nozzles is increased and at the same time the opening movement of the main air valve is retarded to some extent 80 to prevent leaning of the mixture the additional air flow into the secondary mixing chambers through the main air passage, past the throttle valve 94 would be so rapid as to prevent any enrichment of the mixture immediately, and such enrichment is necessary to provide sufficient fuel for proper engine acceleration.

The opening movement of the air valve 95 is retarded primarily for producing at all 90 times, when the throttle 94 is opened, a sufficient pressure differential between the inlet and outlet ends of the primary mixing tubes to create a velocity of flow through such tubes great enough to transport the primary mix 95 ture from the primary mixing chambers to the secondary mixing chambers almost instantaneously. In the device disclosed herein an accelerator pump forces fuel for acceleration into the primary mixing tubes to form 100 a super rich mixture therein. It is a considerable distance from the point where fuel enters the primary mixture passages to the secondary mixing chambers where it is mixed with pure air flowing past throttle 94, and if 105 the air valve 95 were allowed to open freely an appreciable time interval would be necessary for the rich primary mixture to travel through this distance, obviously a greater time interval than that required for the 110 lighter pure air to travel from the throttle 94 to said secondary mixing chambers. By providing means to delay the opening of the valve 95 relative to throttle 94 two results 115 are accomplished, first the production of a high pressure differential between the inlet and outlet ends of the primary mixture passages which maintains a high velocity of flow through such passages at all times; second the retarding of the inflow of pure air to the 120 secondary mixing chambers. By maintaining the high velocity of flow through the primary mixture passages the time interval required for the primary mixture to travel the distance above referred to is greatly reduced. At the same time the retardation of the air 125 flow by means of valve 95 increases the time interval necessary for pure air to reach the secondary mixing chambers, so that these two time intervals approach each other, in fact 130

are substantially equalized, so that the rich primary mixture and the air flowing past throttle 94 reach the secondary mixing chambers at substantially the same time.

5 According to this invention means are provided to retard the opening of the valve 95 which comprises an arm 120 secured outside the housing 18 to the end of shaft 97 on which the valve 95 is mounted. A rod 121 is bent at 10 its upper end to form a short horizontally extending leg 122 which projects through a suitable slot 123 in the free end of arm 120. The slot permits movement of the leg 122 relative to the end of arm 120 as the latter moves 15 in an arcuate path, enabling the rod to move in a rectilinear path. At its lower end the rod 121 is connected to a piston 124 preferably by means of a flanged coupling member 125 pinned to the rod and a nut 126 screwed on 20 said coupling member, the piston being securely clamped between the flange on said coupling member and the nut. The piston has a close sliding fit within a cylinder 127 provided with an attaching flange 128 projecting therefrom which is bolted to the housing 18 as shown in Fig. 8. A vent 129 is provided in the cylinder 127 to allow escape of air on descent of the piston and a spring 130 is received in said cylinder between its bottom and the bottom of the piston, said spring 25 acting to normally hold the valve 95 closed.

It will be noted that according to the present invention the valve 95 is positioned anterior to the throttle 94 and the shaft 97 on 30 which said valve is mounted is placed close to the floor of the passage 81, so that the valve when fully open lies flat on the floor of said passage, the passage 81 being formed with a flat bottom for some distance posterior to said 35 valve as indicated in Fig. 9 to permit the mounting of said valve as described.

When the throttle 94 is closed the engine suction is not communicated to the valve 95 and the spring 130 holds the valve closed. 40 As the throttle 94 opens, however, the engine suction is communicated to points in the passage anterior to the throttle and as soon as the throttle is opened sufficiently for the engine suction effective on said valve 95 to 45 become greater than the force of the spring 130 the valve is opened, moving piston 124 downwardly and forcing the air in the cylinder 127 out through the small hole 129. Owing to the small size of hole 129 it is impossible to lower the piston rapidly and the opening of the air valve is therefore delayed, no matter what the degree of opening of the throttle 94 may be. This retarding means is 50 a simple, efficient and inexpensive form of air dash pot. On closing of throttle 94 the spring 130 will lift the piston and close valve 95.

As previously stated the opening of the 55 valve 95 is temporarily retarded on opening of the main air throttle to accelerate the flow

of primary mixture sufficiently to prevent said mixture from lagging behind the flow of air through the manifold during the acceleration period, thus preventing the formation of a lean mixture at the secondary mixing chambers during the acceleration period. In the device disclosed in this application the primary mixture is enriched by the action of a fuel pump operated simultaneously with the 70 opening of the throttle. This fuel pump forms no part of but is described below to enable a better understanding of the whole charge forming device which is shown in the drawings.

The air valve dash pot, comprising piston 80 106 and cylinder 107 constitutes the pump which operates when the piston moves downwardly on opening of the air valve. A fuel delivery conduit 140 is received at its lower end in a hole in the cylinder 107 near the 85 bottom thereof while the upper, outlet end of said conduit connects with a fuel channel 141 in a block 142, secured in any desirable manner to the bottom of the distributor block in a position somewhat posterior to the primary throttle as indicated in Fig. 3. The block 142 extends across all of the primary mixture passages and fuel passages 143, 144 and 145 formed in said block communicate 90 with passages 146, 147 and 148 drilled in the bottom wall of the distributor block, and communicating with the primary mixture passages 61, 62 and 63 respectively, as shown in Figs. 3 and 13. Two air channels 149, one of which is shown in Fig. 3 admit air to the 100 fuel channel 141 the entering air forming an emulsion with the fuel which issues from passages 146, 147 and 148 into the primary mixture passages.

The reason for admission of air to the 105 fuel channel 141 is to prevent the high suction maintained in the primary carburetors acting to draw fuel from the dash pot cylinder independently of the pumping action of the piston 106. It will be understood that 110 under all conditions of operation a very considerable degree of suction is maintained in the primary mixing chambers and unless the fuel delivery passage between the dash pot cylinder and the primary mixture passages 115 is vented to atmosphere at some point therein, this high suction would operate to lift fuel from the dash pot cylinder at all times, whereas it is desirable to deliver fuel from the dash pot cylinder to the primary mixture passages only when the throttle is opened to cause downward motion of the piston 106. By admitting air to the fuel channel 141 the suction effective to lift fuel through the conduit 140 is never great enough to lift the fuel to the channel 141, but is sufficient to lift fuel 120 only to some point intermediate the dash pot cylinder and said channel preferably to a point immediately below said channel.

When the throttle is opened the suction 130

in the air chamber 80 is increased and air valve 77 and piston 106 are forced downwardly, forcing fuel upwardly through conduit 140 and outlets therefrom to the primary mixture passages during the downward movement of the piston, air being mixed with fuel in channel 141 as previously described. If the dash pot cylinder is provided with the above mentioned by-pass the pumping action continues as long as the piston 106 is in position to close the upper end of the by-pass. As soon as the by-pass is uncovered the pumping action ceases and further downward movement of the piston operates merely to force fuel from the lower part of the cylinder through the by-pass to the upper part of the cylinder.

In addition to the above described devices operating to enrich the mixture for acceleration means is provided for supplying additional fuel at high speed by opening the fuel valve 49 previously referred to. This means comprises an arm 150 pivoted at 151 on the outside of housing 18 as shown in Fig. 8. Projecting from the opposite end of the arm 150, is a pin 152 which is received in a bore in an enlarged head 153 into which the valve 49 is screwed. A cam 154 is fixed on the spindle 67 projecting from the end of the throttle shaft 65 opposite to that on which its operating arm 98 is secured, and cooperating with this cam is a roller 155 mounted for rotation on a pin projecting from the arm 150. A considerable portion of the cam is concentric 35 relative to its operating shaft, so that it is ineffective to raise arm 150 to open the fuel valve until a certain predetermined speed is reached, for example an engine speed corresponding to a vehicular speed of 20-25 miles 40 per hour. By using a cam of different shape the engine speed at which the fuel valve begins to open may be regulated as desired. Also by adjusting the valve in its head 153 the normal position of the valve prior to the 45 opening of said valve by arm 150 may be determined.

The secondary mixing chambers comprise Venturi tubes 160 (as shown) or other flow accelerating elements. There are three of these venturis 160 which are identical in construction and are positioned in the branches 50 11, 12 and 13 of the manifold 10, in such relation to the primary mixing tubes, that the point of greatest depression or suction in 55 each Venturi tube is immediately adjacent the outlet end of the primary mixture tube associated therewith. Each venturi is provided with an annular projecting rib 161 which fits, when the manifold is attached to 60 the engine block, both in the engine intake port and in a recess 162 in the end of the associated branch of the manifold the rib engaging shoulders 163 and 164 in the manifold and intake port respectively when the 65 venturi is in position. A channel 165 is

formed in the outer wall of said venturi at the bottom of said element when the device is assembled, to permit any fuel which precipitates out of the mixture and collects on the wall of the manifold branch to flow into the engine intake port. The Venturi tubes cause the air entering the air manifold to move past the ends of tubes 70, 75 and 76 at high velocity creating in each of the tubes a high suction at all times.

It will be understood that while the device, for retarding the passage of air through the secondary air passage on opening of the air throttle, which constitutes the present invention, is disclosed, for convenience, in this application as embodied in a charge forming device having means for enriching the primary mixture, the invention is in no way limited to such a charge forming device. Such invention will produce desirable results when embodied in a charge forming device in which enriching fuel is not injected into the primary mixture concurrently with the retardation of air flow through the secondary air passage. It will be clear that such air should not be permitted to reach the secondary mixing chambers on opening of the air throttle, before the increased quantity of primary mixture resulting from opening of the primary throttle reaches said mixing chambers, whether said primary mixture is increased in fuel content or not.

While the form of embodiment of the present invention as herein disclosed, constitutes a preferred form, it is to be understood that other forms might be adopted, all coming within the scope of the claims which follow.

What is claimed is as follows:

1. In a charge forming device for a multi-cylinder engine having a plurality of intake ports the combination of a main air manifold having branches leading to said intake ports and forming secondary mixing chambers, a plurality of primary carburetors for supplying fuel mixture to said secondary mixing chambers, a single air intake passage admitting auxiliary air to all of said secondary carburetors, a throttle for controlling the flow through said passage and an automatically operated flow controlling means for modifying the effect of said throttle.

2. In a charge forming device for a multi-cylinder engine having a plurality of intake ports, the combination of a main air manifold having branches leading to said intake ports and forming secondary mixing chambers, a plurality of primary carburetors for supplying fuel mixture to said secondary mixing chambers, a single air intake passage admitting auxiliary air to all of said secondary carburetors, a throttle for controlling the flow through said passage and a suction operated valve in said passage for modifying the effect of said throttle.

3. In a charge forming device for a multi-

- 5 cylinder engine having a plurality of intake ports, the combination of a main air manifold having branches leading to said intake ports and forming secondary mixing chambers, a plurality of primary carburetors for supplying fuel mixture to said secondary mixing chambers, a single air intake passage admitting auxiliary air to all of said secondary carburetors, a throttle for controlling the flow through said passage, a suction operated valve in said passage for modifying the effect of the throttle and means for retarding the opening movements of said valve. 4. In a charge forming device for a multi-cylinder engine having a plurality of intake ports, the combination of a main air manifold having branches leading to said intake ports and forming secondary mixing chambers, a plurality of primary carburetors for supplying fuel mixture to said secondary mixing chambers, a single air intake passage admitting auxiliary air to all of said secondary carburetors, a throttle for controlling the flow through said passage, a suction operated valve in said passage for modifying the effect of the throttle and a dash pot for retarding the opening movements of said valve.
- 10 5. A charge forming device for internal combustion engines having in combination a plurality of secondary mixing chambers, a plurality of primary carburetors for supplying fuel mixture thereto, conduits for conveying the primary mixture to said secondary mixing chambers, means in said secondary mixing chambers for maintaining a high vacuum at the outlets of said primary mixture conduits, a passage for applying auxiliary air to all said secondary mixing chambers only under certain operating conditions and automatic means for retarding the flow of air through said passage when the latter becomes effective to prevent reduction of the vacuum at the outlets of said primary mixture passages.
- 15 6. A charge forming device for internal combustion engines having in combination a plurality of secondary mixing chambers, a plurality of primary carburetors for supplying fuel mixture thereto, conduits for conveying the primary mixture to said secondary mixing chambers, means in said secondary mixing chambers for maintaining a high vacuum at the outlets of said primary mixture conduits, a passage for supplying auxiliary air to all said secondary mixing chambers, a normally closed throttle in said passage, means for opening said throttle at a predetermined engine speed, and automatic means for retarding the flow of air through said passage when the throttle is opened, to prevent reduction of the vacuum at the outlets of the primary mixture passages.
- 20 7. A charge forming device for internal combustion engines comprising a plurality of secondary mixing chambers, a plurality of primary carburetors for supplying fuel mixture thereto, a primary throttle controlling the flow from all the primary carburetors, a secondary air passage for supplying auxiliary air to all said secondary carburetors, a secondary throttle controlling the flow of air therethrough, means operated by the primary throttle for opening said secondary throttle after said primary throttle has opened a predetermined amount, and means for retarding the flow of air through the secondary air passage on opening movement of the secondary throttle.
- 25 8. A charge forming device for internal combustion engines comprising, a plurality of secondary mixing chambers, a plurality of primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a throttle for controlling the supply of mixture, and devices for retarding the flow of air through the main air inlet and secondary air passage on opening movement of the throttle.
- 30 9. A charge forming device for internal combustion engines comprising, a plurality of secondary mixing chambers, a plurality of primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a throttle for controlling the supply of mixture, means for retarding the flow of air through the main air inlet on opening movements of the throttle under all operating conditions, and means for retarding the flow of air through the secondary air passage on opening movements of the throttle under certain operating conditions only.
- 35 10. A charge forming device for internal combustion engines comprising, a plurality of secondary mixing chambers, a plurality of primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a primary throttle for controlling the flow of primary mixture from all of the primary carburetors, an air throttle for controlling the flow through the secondary air passage and an automatically operated flow controlling means for modifying the effect of the air throttle.
- 40 11. A charge forming device for internal combustion engines comprising, a plurality of secondary mixing chambers, a plurality of

primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a primary throttle for controlling the flow of primary mixture from all of the primary carburetors, 10 an air throttle for controlling the flow through the secondary air passage and an automatic suction operated valve in said air passage.

12. A charge forming device for internal combustion engines comprising, a plurality of secondary mixing chambers, a plurality of primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a primary throttle for controlling the flow of primary mixture from all of the primary carburetors, 15 an air throttle for controlling the flow through the secondary air passage, an automatic suction operated valve in said air passage, and means for temporarily retarding the opening movement of said valve on opening movement of the air throttle.

13. A charge forming device for internal combustion engines comprising, a plurality of secondary mixing chambers, a plurality of primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a primary throttle for controlling the flow of primary mixture from all of the primary carburetors, 20 an air throttle for controlling the flow through the secondary air passage, common operating means for opening said primary and air throttles, and means for temporarily retarding the flow of air through the secondary air passage on opening movements of the air throttle.

14. A charge forming device for internal combustion engines comprising, a plurality of secondary mixing chambers, a plurality of primary carburetors in which a primary mixture of fuel and air is formed for delivery to the secondary mixing chambers, a secondary air passage adapted to supply auxiliary air to all of said secondary mixing chambers, a single main air inlet supplying air to all the primary mixing chambers, a primary throttle for controlling the flow of primary mixture from all of the primary carburetors, 25 an air throttle for controlling the flow through the secondary air passage, common operating means for opening said primary

and air throttles including a lost motion connection, whereby the primary throttle is moved independently of the air throttles for a predetermined distance, and means for temporarily retarding the flow of air 70 through the secondary air passage on opening movements of the air throttle.

In testimony whereof I hereto affix my signature.

WILFORD H. TEETER.
